(57) **CLAIM**

The ornamental design for a chair, as shown and described.

DESCRIPTION

FIG. 1 is an isometric view from the front, top and one side of a first embodiment of a chair showing my new design in an unoccupied or rest orientation;

FIG. 2 is a slightly reduced side elevational view thereof from the one side;

FIG. 3 is a slightly reduced side elevational view thereof from the opposite side;

FIG. 4 is a slightly reduced top plan view thereof;

FIG. 5 is a slightly reduced bottom plan view thereof;

FIG. 6 is a slightly reduced front elevation view thereof;

FIG. 7 is a slightly reduced rear elevation view thereof;

FIG. 8 is an isometric view thereof from the front, top and one side of a second embodiment, with the chair in an occupied or use orientation;

FIG. 9 is a slightly enlarged side elevational view thereof with both a cushion and a person occupying the chair being illustrated thereon in phantom line;

FIG. 10 is an isometric view from the front, top and one side of a third embodiment of a chair showing my new design in an unoccupied or rest orientation;

FIG. 11 is a slightly reduced side elevational view thereof;

FIG. 12 is a slightly reduced front elevational view thereof;

FIG. 13 is a slightly reduced top plan view thereof;

FIG. 14 is a slightly reduced bottom plan view thereof;

FIG. 15 is a slightly reduced front elevation view thereof;

FIG. 16 is a slightly reduced rear elevational view thereof;

FIG. 17 is an isometric view thereof from the front, top and one side of a fourth embodiment, with the chair in an occupied or use orientation; and,

FIG. 18 is a slightly enlarged side elevational view thereof with both a cushion and a person occupying the chair being illustrated thereon in phantom line.

In FIG. 8, the two jagged lines in the center are not a part of the claimed design and represent only the indeterminate width of the claimed design.

In FIG. 9, the cushion indicated in phantom line and the person indicated in phantom line are not a part of the claimed design and represent only an environment of use.

In FIG. 17 the two jagged lines in the center are not a part of the claimed design and represent only the indeterminate width of the claimed design; and,

In FIG. 18 the cushion indicated in phantom line and the person indicated in phantom line are not a part of the claimed design and represent only an environment of use.
